CLAIM

The ornamental design for a flower pot cover, as shown and described.

DESCRIPTION

FIG. 1 is a reduced side elevational view of our new flower pot cover design;

FIG. 2 is a transverse sectional view thereof;

FIG. 3 is a reduced bottom plan view thereof;

FIG. 4 is a reduced top plan view thereof;

FIG. 5 is a reduced top plan view of a second embodiment of the design of FIG. 1, the only difference being the shape of the opening;

FIG. 6 is a reduced top plan view of a third embodiment of the design of FIG. 1, the only difference being the shape of the opening;

FIG. 7 is a reduced top plan view of a fourth embodiment of the design of FIG. 1, the only difference being the shape of the opening;

FIG. 8 is a reduced side elevational view of a fifth embodiment of the design of FIG. 1, the only difference being the size of the base; and,

FIG. 9 is a reduced side elevational view of a sixth embodiment of the design of FIG. 1, the only difference being the size of the base.
